UNITED STATES PATENT OFFICE.

BERNARD J. DOWD, OF HARTFORD, CONNECTICUT, ASSIGNOR TO ROYAL TYPEWRITER COMPANY, INC., OF NEW YORK, N. Y., A CORPORATION OF NEW YORK.

TYPEWRITING MACHINE.

Application filed January 11, 1923. Serial No. 612,117.

To all whom it may concern:

Be it known that I, BERNARD J. Dowd, a citizen of the United States, residing in Hartford, in the county of Hartford and State of Connecticut, have invented certain new and useful Improvements in Typewriting Machines, of which the following is a specification.

This invention relates to typewriting machines in which the platen is shifted from one position to another for case printing. In the Royal standard machine, the platen is supported on a carriage which is shifted vertically for this purpose. One or more shift keys are connected with the carriage by mechanism which normally holds the carriage in lower position, but which when a shift key is depressed causes the carriage and its platen to be raised to upper case position. In the Royal machine also mechanism is provided operated by a shift key for locking the platen in upper case position until released, when the carriage lowers by gravity to lower position. In the Royal machine in order to counterbalance the weight of the carriage so that the load on the shift key may be reduced, a spring is connected with the shift mechanism and is put under such tension as to tend to raise the carriage and to thus assist in the shifting operation. Such mechanism has been found to operate efficiently, but I have found that the action may be so refined as to provide a cushion for the shift key after the carriage has been raised to its full extent and at the same time provide means for imparting an initial impulse to the return movement of the carriage. I have also found that the return movement of the carriage may be further assisted by employing a supplemental spring which is normally inactive but which is put under tension when the carriage has nearly reached the limit of its upward movement.

In carrying out my invention in the preferred way, my improvements are applied to a machine of the Royal type having the shift mechanism above mentioned, but the connection between the counterbalancing spring and the shift mechanism is such that when the carriage has been raised to its full extent and after the spring has been relaxed, said spring is again automatically placed under tension and thus affords a cushion for

the shift key and means for giving an initial impulse to the return movement of the carriage.

In the accompanying drawings:—

Figure 1 is a side elevation of parts of a Royal typewriting machine showing the usual shift mechanism modified to include my improvements. In Figure 1 the parts are in the normal lower case position.

Figure 2 is a view of parts of the shift mechanism as they appear when the carriage is raised to its full extent for upper case printing.

Figure 3 is a view of the same mechanism showing how the depression of a shift key is cushioned after the carriage has been raised and how the counterbalancing spring is put under tension for the purposes above mentioned.

Figures 4, 5 and 6 are views of the counterbalancing spring.

Figure 4 illustrates the normal condition of the spring when it is placed under tension and tends to raise the carriage.

Figure 5 illustrates the condition of the spring when the carriage has been raised to its full extent and the tension of the spring is fully relaxed.

Figure 6 illustrates the condition of the spring after the carriage has been raised to its full extent and the shift key is further depressed, thus placing the spring under tension, though not as great as the normal tension of the spring in the lower position of the carriage.

Figure 7 is a detail view in section on the line 7—7 of Figure 2.

Figure 8 is a detail view of the cushion setting member forming part of the connection between a shift key and the mechanism for raising the carriage.

Figure 9 is a detail view showing a modified form of cushion setting device and a modified way of connecting said device with the carriage raising mechanism.

I have shown in Figure 1 only such parts of a typewriting machine of the Royal type as is necessary to illustrate how my improvements may be applied. The machine frame is indicated at A, the carriage at B and the platen at C. The carriage is supported on a shift rail D which has downwardly extending legs E connected at their lower

ends with links F and connected near their upper ends with rocker arms H on a rock shaft k.

The upwardly extending arm k of the shift key K is connected by an adjustable link L with another link M in turn connected at its rear end with one of the rocker arms H in the manner hereinafter described. The arm k is also connected by a link N with a latch O adapted to engage a bracket P on one of the legs E and to hold the carriage in lower position. When the shift key is depressed, the latch is first withdrawn and then the rocker arms H are so moved as to raise the carriage. It will be observed that there is a certain lost motion at m between the link M and its connection with the rocker arms permitting the latch to be withdrawn before the shift key is fully operated to raise the carriage.

In order to hold the carriage in upper case position I preferably employ the usual dog Q which is normally inactive but which engages the bracket P and holds the carriage in raised position when the shift lock key R is operated. The shift lock mechanism indicated at S is of the usual kind and operates in the usual way.

As in the Royal machine, the weight of the carriage is partially counterbalanced by a spring T connected with the machine frame and with the shift mechanism. This spring is normally under tension and tends to lift the carriage but is not sufficiently strong to do so. It, nevertheless, facilitates the lifting operation of the shift keys. When the carriage is raised to its full extent, the tension of the spring is fully relaxed and when the shift key is released, the carriage returns solely by gravity. I have now provided means whereby the spring serves not only to counterbalance or aid in lifting the carriage, but also facilitates its return by giving an initial impulse to the return movement. I do this by means of devices which put the spring under tension immediately after the carriage is raised to its full extent, such tension serving to give an initial impulse to the return movement of the carriage. These devices also provide a cushion for the shift keys inasmuch as after the carriage has been raised to its full extent by the depression of a key, the further movement of the key which puts the spring under tension is cushioned during such operation.

The spring T is connected at one end to a toothed plate U pivoted at u to the machine frame and adjusted by means of the screw U'. These devices are well known features of the Royal machine. The opposite end of the spring T is connected with a cushion setting member V, in this instance consisting of a lever pivoted at v to the lower end of a rocker arm H and having a downwardly

extending arm v' pivotally connected at m to the link M. The spring T is connected with the member V at v² and this member has an upwardly and forwardly extending arm v³ carrying a pin v⁴ working in an inclined slot h' in the rocker arm H. The member V has an arm o connected by a spring o' with the latch O, the construction being such that the latch is held in secure engagement with the bracket P by said spring and also by the spring T through the member V.

The upward movement of the carriage is limited by one or more stops W mounted on the machine frame and engaging one or more brackets W' on the carriage shift mechanism, and the downward movement of the carriage may be limited by one or more stops Y suitably placed.

In Figure 9 I have shown a modified form of cushion setting device. In this case the spring T engages an upwardly extending arm of the member and the upper rear end of this arm is formed with a hook engaging the rocker arm H. The operation is substantially the same.

In order to further assist in the return movement of the carriage I employ one or more springs X which is connected to the carriage shift mechanism and extends downwardly therefrom, being provided at its lower end with an elongated loop x enclosing an adjustable eccentric x' secured to the machine frame. Normally the loop does not engage the eccentric but when the carriage is raised the lower end of the loop comes in contact with the eccentric and during the last part of the upward movement of the carriage the spring is put under tension so that when the shift key is released, the spring X serves to assist in the return movement, which return movement is also assisted by the spring T as before explained.

When the mechanism is in the condition shown in Figure 1 and a shift key is depressed, the latch O is first withdrawn and then by the further downward movement of the shift key, the carriage is raised to its full extent against the stop W. During this upward movement of the carriage, the tension of the spring T is fully relaxed and the mechanism is in the condition illustrated in Figure 2. During this part of the operation the pin v⁴ maintains its position in the slot h'. As the shift key is further depressed, the pin v⁴ moves downwardly and rearwardly in the slot h' causing the member V to turn on its pivot v and thus put the spring T under tension. While this is being done, the shift key is efficiently cushioned and at the same time a force is stored which assists in the return movement of the carriage because as soon as the shift key is released, the spring T now under tension imparts an initial impulse to the carriage and this force

together with that of gravity enables the carriage to quickly return to normal position. Furthermore, during the operation the spring X is put under tension and also 5 assists in the return movement.

When it is desired to lock the carriage in upper case position, the shift lock mechanism R, S, and Q is operated in the usual way.

10 Means for cushioning the shift keys have heretofore been used. Devices for this purpose are shown in patents:—1,226,770; 1,227,438; and 1,244,729 issued to Royal Typewriter Company, Inc., but these devices involve yielding means in the connections 15 between the shift keys and the carriage lifting mechanism, whereas my improvements involve the use of the counterbalancing spring for this purpose, which has the advantage 20 of applying the cushioning effect and the carriage return power directly to the shift mechanism.

It will be observed that the spring T is 25 normally under tension, that when the carriage is raised to its full extent the spring tension is relaxed, and that as the shift key is further depressed the spring is again put under tension. When the shift key is released, the spring T is again relaxed and 30 immediately afterwards put under tension as the carriage assumes its normal position.

While the drawings show only one shift key, it will be understood that two shift keys 35 may be employed as in the usual Royal construction.

By my improvements I am able to give an increased tension to the counterbalancing spring inasmuch as after the carriage is raised to its full extent, the spring is put 40 under tension which assists in the return movement of the carriage. I am thus able to obtain a livelier and more responsive return of the carriage with an eight ounce key depression than has been heretofore possible in a key action having eleven ounce 45 weight action.

It will be observed that the spring X becomes active during the time that the spring T is inactive or relaxed and thus serves most 50 efficiently to assist in the return movement of the carriage before the spring T again becomes active or tends to impede the return movement.

It will be understood that while the invention has been illustrated as applied to a 55 machine in which the entire carriage is raised and lowered for case printing, and in which the carriage therefore constitutes the shiftable element, it is also applicable to machines in which only a portion of the carriage or a platen supporting frame, or a type bar segment, constitutes the shiftable 60 element.

I claim as my invention:

65 1. In a typewriting machine, a member

shiftable for case printing, means for shifting said member, a spring for partially counterbalancing the weight of said member, and means acting when said member is shifted to tension said spring to give an 70 initial impulse to the return movement of the carriage.

2. In a typewriting machine, a platen, printing mechanism, means for effecting a relative case shift movement between the 75 platen and the printing mechanism, a counterbalancing spring for assisting said shift movement, and means acting when said shift movement is effected to tension said spring to give an initial impulse to the return movement of the shifted element.

3. In a typewriting machine, a shiftable element, means for shifting the same for case printing, a counterbalancing spring for assisting the shifting movement, and means 85 whereby the spring is tensioned after the completion of the shifting movement to give an initial impulse to the return movement of the shifted element.

4. In a typewriting machine, a shiftable 90 platen, key operated means for shifting the same, a counterbalancing spring for assisting the shifting movement and which reaches relaxed condition at the end of said movement, and means whereby the spring 95 is again tensioned after the completion of the shifting movement to cushion the key and to give an initial impulse to the return movement of the platen.

5. In a typewriting machine, a platen, key 100 operated means for shifting the same, a stop for limiting the shifting movement thereof, a counterbalancing spring which assists said movement and reaches relaxed position when the movement is limited by said stop, and means whereby the spring is again tensioned after the completion of the shifting movement to give an initial impulse to the return movement of the platen.

6. In a typewriting machine, a platen, a 110 key operated means for shifting the same, a counterbalancing spring for assisting said movement and which reaches relaxed position at the end of the movement, means whereby the spring is again tensioned after the completion of said movement and a second spring which is tensioned only during the latter part of the shift movement, said springs operating to give an initial return impulse to the platen after the release of 120 the key.

7. In a typewriting machine, a carriage, key operated means for shifting the same, a counterbalancing spring for assisting said movement, and means interposed between the spring and the shifting means to tension the same after the shifting movement of the carriage is completed, and to cushion 125 the key.

8. In a typewriting machine, a carriage, 130

- key operated means for shifting the same, a spring for partially counterbalancing the weight of the carriage, and a cushion setting member interposed between the spring and the shifting means and which is moved after the carriage has completed its shifting movement, thereby tensioning the spring and causing the same to give an initial impulse to the return movement of the carriage.
9. In a typewriting machine, a carriage, a shiftable support therefor, a cushion setting member pivotally mounted on said support, a counterbalancing spring one end of which is connected to said cushion setting member, and means for operating said cushion setting member to first shift the carriage and thereafter again tension said spring to cause it to give an initial impulse to the return movement of the carriage.
10. In a typewriting machine, a carriage, a shiftable support therefor, a cushion setting member pivotally mounted on said support, means for limiting the independent movement of said cushion setting member, a counterbalancing spring one end of which is connected to the cushion setting member, a shift key, means connecting the shift key to the cushion setting member whereby the depression of the key first moves the carriage through the cushion setting member and afterwards moves the cushion setting member independently of the support causing the spring to tension and cushion the key.
11. In a typewriting machine, carriage shift mechanism, means for operating the same, a spring for partially counterbalancing the weight of the carriage, and a cushion setting member which is pivotally connected to the carriage shift mechanism, is connected to the counterbalance spring, and has an arm having a lost motion connection with the carriage shift mechanism to permit the spring to cushion the movement of said operating means.
12. In a typewriting machine, the combination with the platen carriage of rocker
- arms for lifting the carriage, a cushion setting member pivotally connected with one 50 of said arms and having a part with a shifting connection with said arm, a counterbalancing spring connected with said cushion setting member, a shift key and connections between the shift key and said cushion setting member.
13. In a typewriting machine, a carriage, shift mechanism therefor, a counterbalancing spring which relaxes as the carriage reaches fully shifted position, and another 60 spring directly connected with the carriage for assisting the return movement which is normally inactive but becomes active as the counterbalancing spring moves to relaxed position.
14. In a typewriting machine, the combination of a platen carriage, lifting devices therefor, a latch for normally holding the carriage in lowered position, a counterbalancing spring for the carriage, a cushion setting device to which the counterbalancing spring is connected, and a yielding connection between the cushion setting device and the latch.
15. In a typewriting machine, the combination of a platen, shifting mechanism therefor, a counterbalancing spring, a cushion setting device carried by the shifting mechanism and connected to the counterbalancing spring to tension said spring 70 after the completion of the shifting movement, a latch for holding the platen in lowered position, and a connection between the latch and the cushion setting device.
16. In a typewriting machine, case shift 75 mechanism, means for operating the same, a key for actuating said means, and a spring which assists the shifting operation and passes from an extended to relaxed position upon the case shift movement, and means to 80 then extend the spring upon a complete depression of the key.
- In testimony whereof, I have hereunto subscribed my name.

BERNARD J. DOWD.
